Patented Oct. 1, 1918.

21 Inventor:
9 Peter O. Holmgren
By Wm. F. Bell Aug.

UNITED STATES PATENT OFFICE.

PETER O. HOLMQUIST, OF CHICAGO, ILLINOIS.

LAUNDRY-BENCH.

1,280,225.

Specification of Letters Patent.

Patented Oct. 1, 1918.

Application filed March 11, 1918. Serial No. 221,592.

To all whom it may concern:

Be it known that I, PETER O. HOLMQUIST, a citizen of the United States, residing at Chicago, in the county of Cook and State 5 of Illinois, have invented certain new and useful Improvements in Laundry-Benches, of which the following is a specification.

This invention relates to laundry benches and has for its primary object the provision 10 of a light folding bench of strong and rigid construction and having stiffening means for the movable sections.

Further objects and advantages of my invention will be apparent as it is better understood by reference to the following specification when read in connection with the accompanying drawing illustrating the preferred embodiment thereof, in which—

Figure 1 is a view in perspective of the 20 bench;

Fig. 2 is a detail in elevation illustrating the stiffening means, and

Fig. 3 is a detail in horizontal section of the structure illustrated in Fig. 2.

Referring to the drawing my improved laundry bench comprises a central section 5 and relatively movable sections 6 and 7 on either side thereof, and adapted to support various receptacles such as tubs, baskets and 30 so forth.

The central section 5 comprises two pairs of converging legs 8 and 9 connected by rods 10 and 11. Cross bars 12 connect the rods 11 to maintain the legs 8 and 9 in 35 spaced relation and to stiffen the structure.

The movable sections comprise supporting bars 13 pivotally mounted on the rods 11 adjacent their inner ends and connected at their outer ends by rods 14. Rods 15, also 40 connecting the supporting bars 13 adjacent their outer ends, pivotally support depending legs 16 which are braced by rods 17 near their lower ends. The rods 10 and 17 are connected by brace bars 18 which hold 45 the legs 16 rigidly in supporting position while the bench is in use.

The cross bars 12 are connected by a medial rod 19 which projects beyond the cross bars forming stop lugs 20 adapted to be en-

gaged by the inner ends of the supporting 50 bars 13 which are recessed at 21 to fit snugly about the stop lugs. When the movable sections are in operative position the inner ends of the supporting bars 13 are braced by engagement with the stop lugs 20 so that the 55 entire bench is stiffened and rendered capable of withstanding the stresses to which it is subjected in use as will be readily understood. When the bench is not in use, the sections 6 may be folded upwardly as indicated at the right in Fig. 1, so that the bench may be compactly arranged for storage until it is again required for use.

Various changes may be made in the form, arrangement and construction of the parts 65 without departing from the spirit and scope of the invention or sacrificing any of its material advantages, the form hereinbefore described being merely the preferred embodiment thereof.

I claim:

1. A laundry bench comprising a central section having pairs of converging legs and cross bars connecting said legs, movable sections having their ends pivotally supported 75 between said legs and cross bars, and means for steadyng the movable sections including stop lugs on said cross bars and adapted to be engaged by the ends of said movable sections when the latter are disposed in supporting position.

2. A laundry bench comprising a central section having pairs of converging legs and cross bars connecting said legs, movable sections having their ends pivotally supported 85 between said legs and cross bars, said movable sections including supporting bars and legs pivotally attached thereto and means for steadyng said movable sections including a rod connecting said cross bars and extending beyond the same in the path of the ends of said supporting bars and adapted to be engaged thereby when said movable sections are disposed in operative position.

PETER O. HOLMQUIST.

Witnesses:
